RAYMOND L. O'CONNOR, OF OAKLAND, CALIFORNIA

DESIGN FOR AN ORNAMENT FOR RADIATOR CAPS OR THE LIKE

Application filed June 10, 1930. Serial No. 36,007. Term of patent 3½ years.

To all whom it may concern:

Be it known that I, RAYMOND L. O'CONNOR, a citizen of the United States, and a resident of the city of Oakland, county of Alameda, State of California, have invented a new, original and ornamental Design for an Ornament for Radiator Caps, or the Like, of which the following is a specification, reference being had to the accompanying drawing, forming part thereof.

Figure 1 is a side elevation showing my new

design for an ornament for radiator caps, or the like.

Figure 2 is a front elevation thereof, and

Figure 3 is a plan view of the said ornament.

I claim:

The ornamental design for an ornament for radiator caps, or the like, substantially as shown.

RAYMOND L. O'CONNOR.
